UNITED STATES PATENT OFFICE

FRED W. PULLEN, OF GRAND RAPIDS, MICHIGAN, ASSIGNOR TO BISSELL CARPET SWEEPER COMPANY, OF GRAND RAPIDS, MICHIGAN

CARPET-SWEEPER CASE

Application filed March 25, 1927. Serial No. 178,284.

This invention relates to improvements in carpet sweeper cases.

The objects of the invention are:

First, to provide a simple and economical construction especially adapted to a case with a sheet metal shell or similar sheet construction.

Second, to provide improved means of assembling such a structure so that the different parts can be finally finished before they are assembled.

Third, to minimize the number of nails or securing devices used.

Objects pertaining to details and economies of my invention will definitely appear from the description to follow. The invention is defined in the claims.

A structure embodying the features of my invention is illustrated in the accompanying drawing, in which:

Fig. 1 is a side elevation of my improved carpet sweeper case, the relation of certain parts being indicated by dotted lines.

Fig. 2 is an end elevation view from the right hand of Fig. 1, the position of certain parts being indicated by dotted lines.

Fig. 3 is a longitudinal detail sectional view through the center of the case showing the method of assembly.

Fig. 4 is a detail side elevation of one of the side bars, the positioning of the longitudinal groove and cross gains being indicated by dotted lines.

Fig. 5 is an enlarged detail perspective view of one end of one of the side bars.

Fig. 6 is a vertical detail sectional view of the preferred form of assembly, dotted lines indicating the method of manufacture and assembly.

Fig. 7 is a detail view of the end and top bar in disassembled relation showing the joint appearing in Fig. 6.

Fig. 8 is a detail sectional view similar to Fig. 6 slightly modified, showing no case end depression for receiving the end of the top bar.

Fig. 9 is a detail view of a disassembled modified joint between the top bar and case end with a rabbet groove to receive the end of the top bar.

The parts will be referred to by their numerals of reference which are the same in all views.

1 is the sheet metal top and side walls of the case. 2, 2 are the ends which each contains a central slot 21 for the accommodation of the brush spindle and apertures 22, 22 for the play of the usual spring axles for the floor wheels. 23 is the hole for the inturned end of the handle bail. 24 is a slight stamped depression for the end of the top bar.

3, 3 are side bars which are grooved at 31 at the top to receive the lower edge of the sheet metal case wall 1 and stiffen and retain the same in place. The ends of the sheet metal case are turned into beads 11, see detail in Figs. 6 and 8. The case ends are inserted in place and the lower corner of each secured by nails 12 in the extreme lower edge. The side bars 3, which contain vertical gains 32 to receive the ends, are put in place and secured by nails 34.

The top bar 4 is then forced to place, depressions 24 having been stamped into the ends 2 to receive the same. The top bars are sprung to place and force the ends 2 securely against the beads 11, completely finishing the ends by that operation. While the top bar will remain in place, due to the tension, it is preferred to secure the same by a wire nail 41, see Figs. 6 and 8.

A rabbet 25 may be cut in the upper edge of the end 2 and the top bar 4 be swung into it as seen in Fig. 9.

It will thus be seen that the case structure is very staunch, the sheet metal is supported under tension, the beads formed on the ends of the same embracing the joint with the end completely encasing the same, making it possible to finish the exterior of the sheet metal case before assembly. As the nails are concealed, except those through the side bars, the structure can be assembled after it is finished very expeditiously. The side bars 3 extend at 33 to receive the usual guard bars.

I would state that the structure as described is clearly capable of considerable modification without departing from my invention. Sheet metal is specified and is es-

pecially adapted. Other sheet material is, however, available.

Having thus described my invention what I claim as new and desire to secure by Letters Patent is:

- 5 1. A carpet sweeper case comprising a rectangular sheet metal shell body with downturned sides and having inturned beads at the ends thereof, case ends conformed to the said shell and having central depressions in their upper inner margins, and retaining nails through the lower corners of the shell body into said ends, side bars grooved at their top to receive the downturned edges of the sheet metal shell and gained to engage the said case ends and secured to said case ends, and a tight fitting top bar within said shell disposed in the depressions in the said case ends and retained in said case by nails through the said ends for clamping the said case ends within the shell, as described.
- 10 2. A carpet sweeper case comprising a rectangular shell body with downturned sides and having inturned beads at the ends thereof, case ends conformed to the said shell and retained by nails through the lower corners of the body shell, and a tight fitting top bar within said shell retained in said case by suitable means for clamping the said case ends within the shell, as described.
- 15 3. In witness whereof I have hereunto set my hand.

FRED. W. PULLEN.
